TEMPORARY BINDER FOR SHEETS OF
PAPER AND THE LIKE

Francis Basil Bolton, Brisbane, Australia

Application October 16, 1934, Serial No. 748,470
In Australia December 18, 1933

2 Claims. (Cl. 129—1)

The object of this invention is to provide means whereby sheets of paper, such as letters and invoices, newspapers, catalogues and the like may be temporarily bound, and whereby such binding will enable sheets to be easily and quickly withdrawn or inserted in the binding in any selected position, and whereby the binder when locked upon the sheets will hold them tightly, and they may be quickly released when required.

10 The invention primarily resides in the employment of two back plates, one having its sides for a short distance turned in to form parallel guides wherein the other plate may slide enabling variation of the depth of the back. Each back 15 plate at its outer end has an anchor plate at right angles to it; one anchor plate has two or more rods and the other anchor plate two or more tubes, which rods and tubes are parallel with the back plates and are telescopic. Means may 20 be provided for limiting the travel of the back plates and further means may be provided whereby such limiting means may be released to enable the two back plates and attached parts to be taken apart.

25 The invention will now be described with reference to the accompanying drawing, wherein:—

Figure 1 is a pictorial view of a preferred construction of binder with covers;

Figure 2 is a pictorial view of the binder in 30 extended position;

Figure 3 is a detail view of the back plates together with rods and tubes and means for restricting their sliding movement;

Figure 4 is a detail view showing a modification 35 of the lower anchor plate adapted for hinging to the cover.

The covers A may be of cardboard, wood or other suitable material, and as shown in Figure 1 may have four hinges A₁. The lower anchor 40 plate B is integral with back plate B₁, and upper anchor plate C is integral with back plate C₁. Lower anchor plate B is secured to cover A by rivets or other suitable means and the inturned edges B₂ of back plate B₁ act as guides for back 45 plate C₁ which is free to move longitudinally within a limited distance. A string D provided with enlarged stop piece or projection D₁ is secured at one end D₂ to back plate B₁ and lies in a slot therein so that normally the projection D₁ 50 contacts with the end of slot C₂ in back plate C₁ when in fully extended position (see Figure 3). By depressing projection D₁ behind the end of slot C₂ the back plate C₁ may be taken completely apart from back plate B₁. Rods E are 55 secured at right angles to lower anchor plate B,

and tubes F are secured to upper anchor plate C, the latter tubes F being slotted at F₁ and adapted to telescope with the rods E which are provided with a series of teeth E₁. A movable plate G provided with holes G₁ is slidably mounted on rods 5 E and tubes F. The holes G₁ have slots G₂ extending laterally therefrom as shown in Fig. 2 and slits G₃ are provided to render one wall of the slots G₂ free to move. This one wall provides a struck-up spring-like tongue to resiliently 10 receive the rods and tubes in slot G₂. With this construction, the plate G may be longitudinally displaced to shift the rods E and tubes F from the holes G₁ partially into the slots G₂ which 15 enlarge, due to the resiliency of the one wall afforded by slit G₃. When in this position, the edge of slot G₂ lies between teeth E₁ and locks plate G against movement along the rods and tubes. The holes G₁ are of such diameter relative to rods E and tubes F that when the latter 20 are in the holes G₁, the plate will be free to move along the rods and tubes. At this point, it will be noted that the upper anchor plate C is provided with opening E₂ to accommodate rods 25 E and teeth E₁. The spring plate H secured to anchor plate B is provided to force papers up against the plate G and maintain it in contact with teeth E₁ when locked. As shown in Figure 1 a locking bar casing J is secured to the cover and has holes J₁ adapted to register with the 30 extended ends of rods E when the covers are folded together and the rods E and tubes F are fully telescoped. A locking bar J₂ sliding within casing J has holes J₃ also in register with holes J₁.

In use the binder is preliminarily opened as in Figure 1 by sliding bar J₂ back and disengaging the sides of slots J₃ therein from the spaces between teeth E₁ on rods E. The cover is thrown back and back plates B₁ and C₁ are allowed to lie against the cover back so that the lower 40 anchor plate B and upper anchor plate C are erect and rods E and tubes F are horizontal. This is possible owing to the four hinges A₁ in the cover, but may be accomplished by hinging the lower anchor plate B at one side instead of 45 fastening it as previously described (see Figure 4). The locking plate G is moved laterally so that the spring controlled slots G₂ disengage the teeth E₁ on rods E, said plate G then being taken up towards upper anchor plate C for the time 50 being. The upper anchor plate C is extended away from the lower anchor plate B by rods E sliding in tubes F and back plate C₁ sliding in back plate B₁ until stopped by projection D₁ on spring D coming into contact with the end of slot 55

C₂ (see Figure 3). If it is desired to completely remove upper anchor plate C and attached parts the projection D₁ is disengaged from the slot C₂, but generally this is not required and the insertion of further papers or withdrawal of same or all may be done with facility if the holes in the sheets are punched to register with rods E and tubes F and are cut from the hole to the edge of the paper. It will be appreciated that the enlargement of the space between anchor plates C and B allows ample room for manipulation of the papers in filing them in proper position, and that when the space is made normal by closing the upper and lower anchor plates B and C together and pressing the papers down by plate G and locking them by sliding said plate along until spring controlled slots G₂ engage teeth E₁ a very firm and secure binding is effected.

I claim:

20 1. A loose leaf binder comprising a pair of hinged covers, an upper and lower anchor plate mounted on one of said covers, a back plate extending substantially perpendicular from each of said anchor plates adapted to engage each other 25 in reciprocable relation, longitudinal slots in each of said back plates adapted to normally register with each other, a spring tongue secured at one end of one of said slots, a projection at one end

of said tongue adapted to ride in said other slot and to maintain the contact between said plates when in extended position, a plurality of rods and corresponding tubes extending substantially perpendicular from said anchor plates and adapted to telescope, teeth on each of said rods and a cooperating slot in each of said tubes, said teeth adapted to project through said slots, slots in said upper anchor plate for penetration by said rods, a locking bar having combined holes and resilient sided slots, the former for accommodating said rods and tubes and the latter for engaging said teeth when said bar is moved longitudinally, and a flat spring secured to said lower anchor plate and adapted to press upwards against the material to be inserted in said loose leaf binder. 5 10 15

2. A loose leaf binder according to claim 1, wherein the ends of said rods are slotted and adapted to pass through said tubes and through openings of said upper anchor plate and wherein the other of said covers is provided with a casing, a sliding bar in the casing having holes respectively, for accommodating the extended rod ends and for engaging the slots in the ends of said rods. 20 25

FRANCIS BASIL BOLTON.
